United States Patent Office

Des. 211,278
Patented June 4, 1968

211,278

WALK AND GARDEN LIGHT

Mitchell Bobrick, Pacific Palisades, Calif., assignor to
Avis Industrial Corporation, Madison Heights, Mich.,
a corporation of Delaware

Filed Apr. 7, 1967, Ser. No. 6,584

Term of patent 14 years

(Cl. D48—31)

FIG. 1 is a front elevational view of one embodiment of the light;

FIG. 2 is a side elevational view;

FIG. 3 is a top plan view;

FIG. 4 is a bottom plan view; and

FIG. 5 is a front elevational view of another embodiment of the light.

I claim:

The ornamental design for a walk and garden light, as shown and described.
